UNITED STATES PATENT OFFICE.

ARTHUR ATWATER KENT, OF PHILADELPHIA, PENNSYLVANIA.

ELECTRIC CONTACT DEVICE.

1,152,642.

Specification of Letters Patent.

Patented Sept. 7, 1915.

Application filed December 26, 1905. Serial No. 293,237.

To all whom it may concern:

Be it known that I, ARTHUR ATWATER KENT, a citizen of the United States, residing in the city and county of Philadelphia, State of Pennsylvania, have invented a new and useful Electric Contact Device, of which the following is a specification.

My invention relates to electric contact devices or mechanical vibrators and particularly to such devices as are adapted to be used with the sparking circuits of internal combustion engines.

The object of my invention is to provide a contact device, or mechanical vibrator, especially adapted for the sparking circuit of an internal combustion engine, in which the length of time that the circuit is closed is constant, although the speed of the engine may vary.

20 A further object of my invention is to dispense with the magnetic vibrator ordinarily employed in a sparking circuit.

25 A further object of my invention is to render the operation of the contact device positive and certain and to insure the closure and the instantaneous breaking again of the circuit at the proper point in the revolution of the shaft of the engine.

30 A further object of my invention is to prevent the closure of the circuit at any other than the predetermined time for which the device is adjusted.

35 A further object of my invention is to prevent the resilient or yielding contact arm from vibrating or moving in such a manner as to accidentally engage the stationary contact with which it is adapted to coöperate.

40 A further object of my invention is to construct a contact device in which the setting and releasing of the movable member is controlled by a positively driven actuating mechanism, but in which the returning of the said member is effected by a means independent of said actuating mechanism, to re-45 turn the same to its normal position in a constant interval of time.

Further objects of my invention are to 50 make a device of the character above set forth which is easily assembled, and taken apart, so that a worn or broken part may be 55 readily removed and replaced or adjusted without disturbing the other parts of the device, and to construct the device as simply and cheaply as is consistent with the best results.

It further consists of other novel features

of construction, all as will be hereinafter fully set forth.

Figure 1 represents a perspective view of a mechanical vibrator or electric contact device embodying my invention. Fig. 2 represents a front elevation of Fig. 1. Fig. 3 represents a section on line $x-x$ Fig. 2. Fig. 4 represents a side elevation of the shaft in detached position. Fig. 5 represents a side elevation of another embodiment of my invention.

Similar numerals of reference indicate corresponding parts in the figures.

Referring to the drawings, 1 designates the vibrator comprising the body 2 having the boss or bearings 3 extending from one side thereof and the bearings 4 and 5 from the other side thereof, said bearings having the portion 6 of the shaft 7 rotatably mounted therein, the outer portion or extremity 8 having thereon four notches resembling the notches on a ratchet, said notches, when the parts are assembled, being located in the cut away portion 10 between the bearings 4 and 5, it being assumed, in the present instance, that four cylinders are used. The shaft 7 has an adjustable collar 7' thereon.

11 designates the terminal of the lifter or actuating member 12, the inner end of the latter being located in the recess 13 and abutting against the stop 14, the outer end being supported on the seat 5' of the bearing 5, as will be understood from Fig. 3, said terminal being held in proper position, relative to the notches 9, by the spring or its equivalent 15, one end of the latter engaging a fixed point as 16 and the opposite end engaging or being hooked into the eye 17 of the lifter.

1 A movable circuit closing member comprising a support or a head 18 preferably of polygonal contour, as square in the present instance, is loosely mounted on the pin 19, so as to freely rock on the latter, said head in the present instance having the strip of steel or other material 20, secured thereto, preferably as indicated in Fig. 3, said strip being deflected upwardly to form the member 21 which constitutes a stop against which the yielding or resilient arm or member 22 normally presses. Said member 22 is provided with a platinum contact 23 which is adapted to coact with the stationary contact 24, carried by the screw 25, any improper movement of the parts being prevented by the pin 26. The screw 25 is se-

cured, when in the desired position, by tightening the screw 27. By this construction the resilient arm 22 is placed under tension and prevented from vibrating or trembling, any accidental closing of the circuit through the contact points 23 and 24 is avoided, and a rapid make and break of the circuit is effected.

Referring once more to the strip 20, it will be seen that the latter is deflected laterally to form the member 28, which has the downwardly deflected terminal 29, which is held in proper position on the pin 30 by reason of the spring 31, the free end of the latter resting on the screw 32, which can be adjusted so as to adjust said spring 31, so as to normally keep the points 23 and 24 apart. In the construction seen in Fig. 3, I have shown the strip 20 secured in position by the screws 33 and 34 and I also utilize the latter to hold the end of the spring 31 in place, although it is evident that various other devices may be employed for holding these parts in assembled position. In the present instance, I secure the foot of the arm 22 in position by a screw 35, although it is evident that other devices may be employed and the elbow lever composed of the parts 28 and 21 and their adjuncts may be formed in other ways without departing from the spirit of my invention.

36 designates a spring guard adapted to have its free end snapped over the pin 19, so as to hold the head or movable contact support 18 and its adjuncts in position. This provides a means whereby the whole movable circuit closing member, comprising the support or head 18, the spring 31, the yielding or resilient contact member or arm 22, stop arm 21 and member 28, may be bodily removed without disturbing the other parts of the mechanism. Any one of the said parts may be removed and readily replaced or adjusted after the spring guard 36 has been swung on its pivot laterally and the head, to which the said parts are secured, has been drawn off the pivot pin 19.

It will be evident that the arm 37, which carries the screws 25 and 27, can be readily removed when desired.

In Fig. 5, I have shown a slightly different manner of making the contacts wherein I employ the head, mounted on the pin 19 as before, but omit the contact arm 22 and extend the member 28 upwardly to form the arm 38 having thereon the contact point 39, adapted to coact with the point 40 carried on the resilient arm 41, secured in position by the screw 42, the extent of movement of said arm 41 being adjusted by the screw 43. As all the other parts employed in Fig. 5 are the same as those already described, any further description is unnecessary.

65 The operation is as follows:—The space

between the contacts can be adjusted by proper manipulation of the screw 25, the spring 31 normally keeping the contact points apart. The shaft 7 normally revolves in the direction of the arrow seen in Fig. 3 and as it revolves, assuming the parts to be in the position seen in Fig. 3, it carries forward the terminal 11 of the lifter 12, this forward movement of said lifter causing a tension upon the spring 15. There is no connection made at the contacts while the lifter is going forward but when it is released from the ratchet 8, by reason of the engagement of the lifter with the seat 5, the tension of the spring 15 brings it back to its original position. As the lifter starts in its backward path, it slides upwardly over the top of the ratchet teeth and raises the terminal 29, which causes a contact at 23 and 24, which closes the primary circuit and magnetizes the iron core in the coil (not shown). As the head 18 turns on the pin 19, the yielding or resilient arm or member 22 and the stop 21 against which said arm normally presses, are turned 90 in the direction of the stationary contact 24. The engagement of the contacts prevents any further turning of the resilient arm 22, but the stop 21 moves on and away from the said arm 22, and puts the same arm under a still greater tension, which in conjunction with the spring 31 effects an instantaneous separation of the contact points the moment the lifter 12 passes from under the terminal 29. On the return movement the contacts 23 and 24 remain in engagement until the upper end of the stop arm 21 reengages the resilient arm 22, when they move together to their original 105 position. The resilient arm 22 thus firmly engages the stationary contact 24, under tension, is allowed to dwell there and is then quickly removed therefrom, effecting a very rapid make and break of the circuit, 110 insuring a firm and positive closure long enough to insure a large and hot spark when the circuit is broken. Before the terminal 11 reaches its released position, it allows the terminal 29 to drop, thus breaking 115 the contact, which discharges the magnetism of the core of the coil (not shown) and produces a spark at the plug. When the next notch on the shaft comes around, this operation is repeated making but one spark for 120 every explosion in the engine.

From the above it will be plain that the spring 15 of the lifter arm 12 is brought to tension by the ratchet on the shaft 8, and that on its return movement the lifter arm 12 moves in a different path from that in which it was advanced. In returning, and before it reaches its original position, the said lifter arm 12 is positively forced laterally or transversely into engagement with 130

the movable arm 28, actuating the resilient contact arm 22, by the outer surface of the teeth of the ratchet over which it is drawn by the spring 15.

It will be apparent that although the engine may be turning very slowly and the spring connected with the lifter arm brought very slowly to tension, no contact will be made until the tension of the spring is released. The time which is necessary for the spring to resume its normal position is always constant and the coacting parts are so constructed as to allow a very quick release of this spring. It will thus be readily apparent to those skilled in the art that the make and break of the contact is very rapidly accomplished and that the spark will always be of a constant size immaterial of the speed of the engine and I have found in practice that this contact device may be actuated at a speed much greater than an engine ever attains, since the lifter 12, although advanced at variable speeds dependent upon the speed of the rotating cam 8 driven from the engine, is always returned under the quick influence of the spring 15 so that it traverses that portion of its path of movement in a constant and substantially instantaneous period of time. It will further be apparent that in order to make a spark the lifter arm must be carried forward and released and when the engine is reversed this lifter arm is not carried forward but is simply raised and does not come in contact or engage with the terminal 29 of the member 28 so that when the engine is reversed or running backward no spark will be generated. When the device is in operation the current is made and broken so rapidly that on the lowest speed of the engine the movement of the platinum point which forms the contact can hardly be seen. It will further be apparent that while in the present instance four sparks are made for one revolution of the shaft, the number of sparks per revolution will depend entirely upon the number of notches 9 on the driven member 8. When a four cycle engine is employed this driven shaft 8 would run at half the speed so consequently only one spark would be produced for each explosion.

It will be evident that various changes may be made by those skilled in the art, which may come within the scope of my invention and I do not therefore desire to be limited in every instance to the exact construction herein shown and described.

It will be understood that the arm 37 is insulated from the body 2 by the insulation 44, as will be understood from Fig. 2 and in practice I provide, upon the back of said body, the spring 45, seen in full lines in Fig. 2 and in dotted lines in Fig. 3; and I also in practice, attach to the rear of the arm 37, the spring 46, the relative position

of said spring being apparent from Figs. 2 and 3. The function of the springs 45 and 46 is as follows:—to make connection between the body 2 and arm 37 to the sliding contacts, not shown, which are connected with the rest of the system. I have purposely omitted to show, in detail, all of these various connections as the manner of attaching or securing the device which forms my invention in position, will be familiar to those skilled in the art. It will also be apparent that my present invention is adapted for use by increasing the size and power of the parts for operating points inside of an engine for a low tension make and break system.

It will be apparent from the foregoing that my invention is adapted for use in the jump spark, high tension system and it will be obvious that the principal instrumentalities of which my invention consists can be variously arranged and organized and in the accompanying drawings I have shown one embodiment thereof which I have found in practice to give satisfactory results, although it is to be understood that my invention is not limited to this specific arrangement and organization of these instrumentalities.

Having thus described my invention, what I claim as new and desire to secure by Letters Patent, is:—

1. In a sparking device a support, a resilient member carried thereby, means for preventing the free oscillation of said resilient member independently of said support, an actuating member adapted to move said support, a spring for maintaining said actuating member in normal position, and means for moving said actuating member against the tension of said spring. 100

2. In a contact device, a contact point support, an actuating member for operating the same, means for advancing and releasing said actuating member and for effecting the return of said actuating member in a different path from that in which it was advanced, said support being operated by said actuating member during its return movement, a resilient member carried by said support, a contact carried by said resilient member, means to prevent any movement of said resilient member independent of said support, a contact carried by said resilient member, means first mentioned contact to make and break the circuit. 110

3. In a contact device, a driven member, an actuating member operated thereby, a tension device for said actuating member, means for advancing and releasing said member, means for effecting the return of said actuating member in a different path from that in which it was advanced, a contact point support operated by said actuating member during its return movement, a resilient contact carried by said support, a 125

rigid stop against which said resilient contact normally presses.

4. In a contact device, a driven member, an actuating member advanced thereby, a stop for said actuating member, a tension device for normally maintaining said actuating member against said stop, means for effecting the return of said actuating member in a different path from that in which it was advanced, a pivoted support adapted to be oscillated by said actuating member on the return movement of the latter, a resilient contact member carried by said pivoted support, and a stationary contact co-operating with said resilient contact member to make and break the circuit.

5. In a contact device an actuating member, means for advancing and releasing said member, means for effecting the return of said member, a movable support moved by said actuating member during its return movement, a resilient member carried by said support, a contact carried by said resilient member, and a stationary contact co-acting with said first mentioned contact to make and break the circuit.

6. In a contact device a stationary contact point, a movable contact point, a yielding member on which said movable contact point is mounted, and a stop engaging said member on that side of said member adjacent the other contact point and against which said member normally presses under tension and by which said member is kept under tension when said contacts are out of engagement, an actuating shaft, a reciprocating member for operating said movable contact point, said reciprocating member being advanced by said shaft at a speed dependent upon the speed of said shaft and means to return said reciprocating member at fixed rate of speed independent of the speed of said shaft.

7. In a contact device a rotatable shaft, an actuating member, means to impart from said shaft to said member one movement the rate of which is dependent upon and substantially proportional to the speed of said shaft, means to give said member a second movement the rate of which is substantially uniform and is independent of the speed at which said shaft may be moving, a movable support, a resilient member carried by said support, a contact point mounted on said resilient member, a contact point co-operating with said movable contact point, means mounted on said support and engaged by said resilient member when said contact points are out of engagement with each other to prevent said resilient member from trembling.

8. In a contact device a stationary contact point, a movable contact point, a support therefor, means for moving said support back and forth to intermittently bring said

contact points into operative engagement with each other, said support comprising tension means tending to move said movable contact point toward said stationary contact point, and a stop, carried by said support, to prevent a movement of said movable contact point toward said stationary contact point beyond a predetermined position relative to said support, against which said movable contact point substantially rests when said contact points are out of engagement with each other, and away from which said movable contact point is forced when said points are in engagement with each other.

9. In a contact device a movable contact support, a yielding member carried thereby, a movable contact point carried by said member, a stationary contact point, rotatable means to operate said support, means to cause said movable contact point to engage said stationary contact point for a uniform length of time irrespective of the speed at which said rotatable means is moved and a stop carried by said support against which said member normally presses to limit the movement of said member relative to said support toward said stationary contact point.

10. In a contact device a relatively fixed contact point, a movable contact point, a resilient arm upon which one of said points is mounted, said arm being under tension tending to move the contact point carried thereby toward said other contact point, and a rigid stop against which said resilient arm presses and from which said resilient arm is forced away in opposition to the tension of said arm when said contact points are in engagement with each other.

11. In a contact device, a pair of contact points, a support, a resilient member carried thereby and by which one of said contact points is carried, means to oscillate said support and means carried by said support to hold said resilient member under tension whenever said contact points are separated.

12. In a contact device, a stationary contact point, a movable support, a resilient arm carried thereby, rotatable means to oscillate said support to bring said arm intermittently into operative engagement with said stationary contact point for a constant length of time irrespective of the speed of said rotatable means, and a stop carried by said support against which said arm normally presses and from which it is forced by its engagement with said stationary contact.

13. In a contact device a pair of contact points, a yielding member carrying one of said points, said member being under a tension tending to move it toward the other of said points, a stop against which said member presses when said contact points are out of engagement and from which said member

is pressed by the engagement of said points and means for moving one of said points into and out of engagement with the other of said points.

- 5 14. In a contact device a reciprocatory member, means to reciprocate said member substantially longitudinally, means to cause one end of said member to traverse a substantially looped path, and to cause said end 10 to traverse a predetermined portion of its said looped path at a substantially uniform rate of speed irrespective of the speed at which it traverses other portions of its path and a circuit closing member actuated by 15 said reciprocatory member when said reciprocatory member is traversing that portion of its said looped path at said uniform rate of speed.
15. In a contact device a reciprocatory member, means to reciprocate said member substantially longitudinally, means to cause one end of said member to traverse a substantially looped path, a circuit closing member extending into said path and adapted 20 to engage said end, and means to cause said end to traverse that portion of its path adjacent said circuit closing member substantially instantaneously irrespective of the speed at which it traverses the other portions 25 of its path.

- 30 16. In a contact device a reciprocatory member, means to reciprocate said member substantially longitudinally, and a circuit closing member adapted to be operated by said reciprocatory member at a predetermined point in the path of said reciprocatory member and means to cause said reciprocatory member to traverse that portion of its path in which it operates said circuit closing member at a substantially instantaneous and constant speed irrespective of the speed 35 at which reciprocatory member traverses the other portions of its path.

- 40 17. In a contact device an actuating member mounted to oscillate about one end and also to move bodily longitudinally, a rotatable cam and yielding means for normally holding the free end of said member against said cam and the said member at one end of 45 its path of longitudinal movement.

- 50 18. In a contact device, a stationary contact point, a movable circuit closing member, a contact point carried thereby, a resilient arm on which said last mentioned contact point is carried, a stop on said circuit closing member against which said arm normally presses, means to move said member to cause said points to alternately engage and separate, and a stud upon which said member is 55 mounted and from which it can be bodily withdrawn without disturbing the other parts of said device.

- 60 19. In a contact device a stationary con-

tact point, a movable circuit closing member, a contact point carried thereby, a resilient 65 arm on which said last mentioned contact point is carried, a stop on said circuit closing member against which said arm normally presses, means to oscillate said member to cause said points to alternately engage and 70 separate, and a support upon which said member is mounted and from which it can be bodily withdrawn without disturbing the other parts of said device.

20. In a contact device, a stationary contact point, a movable circuit closing member carrying a contact point, means to oscillate said member to cause said points to alternately engage and separate, a stud on which said member is pivoted, and from which it 80 can be laterally withdrawn without disturbing the other parts of said device, and a spring to yieldingly retain said member on said stud.

21. In a contact device a pair of contact carrying members, a pair of contact points carried thereby, resilient means upon which one of said contact points is supported, a stop against which said means normally presses, yielding means tending to hold said 90 points normally separated, and means acting intermittently in opposition to said yielding means to cause said points to engage, the engagement of said points operating to put one of said members under additional tension 95 and tending to separate said points whenever said points are in engagement and said intermittently acting means are not operating.

22. In a contact device a stationary contact point, a movable circuit closing member, a contact point carried thereby, a resilient arm on which said last mentioned contact point is carried, and a stop mounted on said circuit closing member and against which 105 said arm normally presses under tension tending to move the contact point on said resilient arm toward said stationary contact point.

23. In a contact device a lifter having on one end a hook, a ratchet coöperating with said hook to advance said lifter and to then release the same, a support for the other end of said lifter upon which said lifter is free to slide when advanced by said ratchet 110 and a yielding means for holding said hook in operative position with respect to said ratchet and for holding said other end of said lifter on said seat and tending to hold said lifter in its rearmost position on said 115 seat.
